UNITED STATES PATENT OFFICE

169,577

LUGGAGE TRAY

Clarence S. Burtchaell, Ross, Calif.

Application October 13, 1952, Serial No. 21,814

Term of patent 14 years

(Cl. D87—5)

To all whom it may concern:

Be it known that I, Clarence S. Burtchaell, a citizen of the United States of America and a resident of Ross, county of Marin, State of California, have invented a new, original, and ornamental Design for a Luggage Tray, of which the following is a specification, reference being had to the accompanying drawing, forming a part hereof.

Referring to the drawing:

Fig. 1 is a top perspective view of a luggage tray showing my new design; and

Fig. 2 is a bottom perspective view.

I claim:

The ornamental design for a luggage tray, substantially as shown.

CLARENCE S. BURTCHAELL.
